UNITED STATES PATENT OFFICE.

GEORGE KOHLER, OF SEATTLE, WASHINGTON.

ROOF FIRE-EXTINGUISHER.

1,285,236.

Specification of Letters Patent. Patented Nov. 19, 1918.

Application filed July 31, 1917. Serial No. 183,704.

To all whom it may concern:

Be it known that I, GEORGE KOHLER, a citizen of the United States, residing at Seattle, in the county of King and State of Washington, have invented certain new and useful Improvements in Roof Fire-Extinguishers; and I do hereby declare the following to be a full, clear, and exact description of the invention, such as will enable others skilled in the art to which it appertains to make and use the same.

This invention relates to a fire extinguishing apparatus, and the primary object of the invention is to provide means whereby the roof of a house may be flooded with water, in case of fire, and also to provide means whereby either one side or the other side of a roof may be flooded with water independently of the opposite side.

More specifically, the object of this invention is to provide a pair of pipes which extend along upon each side of the comb of a house roof, and which have slots extending their full lengths substantially parallel with the roof, so as to permit water to exit from the pipes over the roof for the purpose of flooding the latter in case of fire; and further to provide a three-way valve which is positioned at the point of communication between the two pipes and the feed pipe for controlling the passage of the water into either of the comb carried pipes, or into both of them as desired.

With the foregoing and other objects in view, this invention consists in such novel features of construction, combination and arrangement of parts as will be hereinafter more fully described, illustrated in the accompanying drawings and claimed.

In describing the invention in detail, reference will be had to the accompanying drawings wherein like characters designate like and corresponding parts throughout the several views, and in which:—

Figure 1 is a view of a house showing the invention applied;

Fig. 2 is a fragmentary top plan view of the invention;

Fig. 3 is a section through the ground showing the feed pipe extending therein and also illustrating the valve for controlling the operation of the extinguisher;

Fig. 4 is a section through the three-way valve construction;

Fig. 5 is an end elevation of the valve construction; and

Fig. 6 is a section on the line 6—6 of Fig. 1.

Referring more particularly to the drawings, 1 designates the roof of any ordinary house, which roof has an angle iron 2 mounted over the comb of the roof 1, and extending downwardly upon each side of the roof as clearly shown in Figs. 1 and 6 of the drawings. The pipes 3 and 4 extend 65 along the comb of the roof 1 and the pipe 3 is positioned upon one side of the comb while the pipe 4 is positioned upon the other side, as clearly shown in Fig. 6 of the drawings. The ends of the pipes 3 and 4 70 are joined as shown at 5 and 6. The pipes 3 and 4 have a cap or plug 5^a inserted therein, at the joined ends 5 of the pipes, for preventing the water from flowing from the pipe 3 into the pipe 4, when it 75 is desired to flood only one side of the roof of the building. The pipes 3 and 4 are provided with longitudinally extending slots 7, which are substantially parallel to the comb of the roof of the house, so that 80 water flowing out of the pipes will flow over the roof for flooding the same, in case of fire. The ends 6 of the pipes 3 and 4 are connected to a valve casing 8, as clearly shown in Fig. 4 of the drawings. The casing 8 has a valve 9 positioned therein which is provided with a plurality of passageways A, B, C, D, E and F. The feed pipe 10 also 85 communicates with the casing 8, as clearly shown in Fig. 4. When the passageway A 90 is in communication with the feed pipe 10, and the passages B and C in communication with the pipes 3 and 4 respectively, water will be fed to both of the pipes 3 and 4, and when the passageway E is in communication 95 with the feed pipe 10 and the passageway D in communication with the feed pipe 3, which positions are provided by the rotation of the valve 9, the water will be directed only through the pipe 3 and when the passageway F communicates with the pipe 10 and the passageway D communicates with the pipe 4, water will be fed only to the pipe 4, so that by the operation of the valve, 100 the passage of the water outwardly over the roof 1 may be controlled as desired.

The valve 9 projects out of the casing 8, and it has a rod 12 extending diametrically therethrough. Downwardly extending rods 14 and 15 are connected to the ends of the rods 12 and are provided for rotating the valve 9 for controlling the positions of the

various passageways or ducts formed in the valve, and consequently controlling the passage of the water through the pipes 3 and 4.

The pipes 14 and 15 extend downwardly and have flexible members, such as chains 16 or the like connected to their lower ends and connected to a suitable fastening device 17 carried by the side of the house, as clearly shown in Fig. 1 of the drawings.

10 The feed pipe 10 extends downwardly along one end of the house, and into the ground, as clearly shown in Fig. 3 of the drawings. The lower end of the vertical feed pipe 10 is positioned in a box or suitable structure indicated at 19, which is provided for preventing the freezing of the valve structure 20 which controls the passage of water into the feed pipe 10. A key 21 extends upwardly through an opening 22 in the ground, and it has a handle 23 formed thereon, through the medium of which handle and rod the valve 20 is operated for controlling the passage of water into and through the pipe 10.

15 The valve 20 has a pipe 24 communicating therewith which supplies the water to the valve and the pipe 10 and this pipe may be connected to an ordinary water main or to a pump, through the medium of a pipe 25, depending upon the manner in which the water is procured for the house.

20 In case of a fire on the roof of the house, the valve 20 is opened, through the operation of the rod 21, which allows the water to pass upwardly through the feed pipe 10, three-way valve structure 9 and the pipes 3 and 4, out of which it passes through the

slots 7, and floods the roof of the house, for extinguishing any fire thereon.

In reducing the invention to practice, certain minor features of construction, combination and arrangement of parts may necessitate alterations to which the patentee is entitled, provided such alterations are comprehended within the scope of what is claimed.

What is claimed is:—

1. In a fire extinguisher for roofs, a pair of pipes extending longitudinally along the comb of a house roof, one of the said pipes being positioned upon each side of the comb, said pipes provided with longitudinally extending slots parallel to the comb of the roof for flooding the roof with water upon passage of water into the pipes, a feed pipe for delivering water to said roof carried pipes, a valve casing connecting the roof carried pipes and the feed pipe, a rotary valve positioned in the said casing, said valve being provided with a series of passage ways, said valve having one end projecting outwardly from said casing, a rod extending diametrically through the outwardly projecting portion of the valve, and means connected with the said rod to control the passage ways of the valve when admitting water to the roof carried pipes as and for the purpose specified.

In testimony whereof I affix my signature in presence of two witnesses.

GEORGE KOHLER.
